(57) **CLAIM**

The ornamental design for a portable bidet, as shown and described.

DESCRIPTION

FIG. 1 is a front, left and top perspective view of a portable bidet, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is an enlarged view of area "9" in FIG. 1.

The broken lines shown in the drawings illustrate portions of the portable bidet that form no part of the claimed design. The dot-dash broken lines depict the boundaries of the enlargements that form no part of the claimed design.

1 Claim, 9 Drawing Sheets
